CARL OTTO, OF HELLERUP, DENMARK

REGENERATIVE COKE OVEN

Application filed March 10, 1925. Serial No. 14,472.

This invention relates to a regenerative coke oven having a row of horizontally elongated oven chambers which may be heated as desired by strong gas or weak gas and in which each chamber is preferably provided with heating walls having vertical heating flues and with regenerators running below the oven sole, in the direction of the oven chambers. The heating flues are constructed 10 in the form of so-called twin flues or hairpin flues, in one form of which the heating gases burn in alternate flues upwardly and pass downwardly into the associated intermediate flues, during one oven operation, and 15 the reverse direction of burning takes place when the oven is reversed. As the oven is to be heated as desired with either strong gas or weak gas, there are provided in addition to the feeding pipes for supplying 20 strong gas, regenerator chambers for pre-heating and supplying weak gas as well as for preheating the air for combustion. In special cases when it is not desired to heat with a strong gas, the feeding pipes for supplying the strong gas may be omitted.

One of the objects of the invention is to simplify the construction of such coke ovens and to so construct and arrange the gas, air and waste-heat passageways and the regenerators for preheating gas and air and for receiving the waste-heat in connection with twin or hairpin burner flues, so that each group of regenerators supplies preheated air and preheated gas for combustion directly 30 thru short transverse vertical passageways to a plurality of hairpin flues arranged in neighboring heating walls, each air regenerator supplying only its associated heating wall, the gas regenerators supplying the flues 35 in both heating walls from which walls the products of combustion pass as waste-heat into two adjacent groups of regenerators, one group on each side of the feeding group of regenerators. The outside regenerators of a 40 group are connected to the flues of neighboring heating walls and the intermediate regenerator is connected to the flues of both of said walls.

In accordance with the invention, I provide under each oven chamber, three separat-

ed regenerators of which the middle one serves for heating gas and the two arranged at the sides of the middle regenerating, serve to preheat the air. This construction has the advantage that regenerators for gas and waste-heat do not lie side by side and it is, therefore, impossible for gas to leak or flow into the waste-heat regenerators. This avoids dangerous conditions in the oven. Gas and air under an oven chamber pass upwardly into the two heating walls and the waste-gases or products of combustion descend downwardly under the two neighboring chambers.

With this construction, moreover, a separate, independent air regenerator is connected with one half of the heating flues of a heating wall whereas the gas regenerator is connected with the half of the heating flues of both neighboring walls.

As illustrated in the drawings, the regenerators may be divided in the middle of the oven by a division wall, thus forming a double oven. Each longitudinal half of the oven is thus separated from the other half and the heating, coking and gas making operations can take place in each half oven independently of the other. Another subdivision of the regenerators can be made so that, for example, for each burner a special regenerator may be provided.

With the above and other objects in view, my invention consists in the parts, improvements and combinations more fully pointed out hereinafter.

Referring now to the drawings:

Figure 1 illustrates a vertical longitudinal section of the oven.

Figure 2 is a vertical cross-section on line 2-2 of Figure 1.

Figure 3 is a horizontal cross-section on line 3-3 of Fig. 1, the said section passing thru the hairpin flues.

Figures 4, 5, 6 and 7 are detail cross-sectional views on lines 4-4, 5-5, 6-6 and 7-7 of Figure 3.

Figure 8 is a cross-sectional view taken on the same plane of section as is Figure 2.

Figure 9 is a cross-sectional view illustrat-

ing a regulator brick, showing my form of flue regulator.

Figure 10 is a cross-sectional detail view taken at right-angles to Figure 9.

Figure 11 is a horizontal cross-section illustrating another form of the invention, and

Figure 12 is a cross-section on line 12—12 of Fig. 11.

Referring to the drawings, the oven is illustrated as an underburner coke and gas oven carried on supports 2, forming accessible arches or passages under which the attendant may move to regulate the valves for the rich gas supply. The body of the oven comprises a plurality of horizontally elongated oven chambers 3, 3a, provided with heating walls 4, 4a, in which twin heating flues, 5, 6, 5a, 6a, 5b, 6b, are arranged, the gas burning upwardly in the branch flues 5, 5a, 5b, and descending in flues 6, 6a, 6b, in one wall, and when the oven is reversed, the gases will burn upwardly in flues 6, 6a, 6b, and descend in flues 5, 5a, 5b. The flues are provided at their tops with peep holes. Regulators are provided for regulating the flow thru the flues, which regulators may be constructed as usual, in the form shown in Figure 1, in which slides 7, are provided whose position can be adjusted by a rod operated manually and passing thru holes 8, in the top of the oven. I prefer to employ my type of regulator illustrated in Figures 9 and 10, which will be described later.

Running underneath the heating flues in the direction of the oven chambers, a plurality of groups of regenerators is provided, the regenerators of each group serving to preheat the air and the weak gas for the twin flues of two neighboring heating walls between which the oven chamber lies. Some of these groups of regenerators are numbered 10, 11, 12, 13, in Figure 8. Each group of regenerators includes a weak gas regenerator between two air regenerators. Triad group 11, includes gas regenerator 14, built between two air regenerators 15, 16. Triad group 12, includes gas regenerator 17, built between two air regenerators 18, 19. Triad

group 10, includes gas regenerator 21, and two air regenerators 20, 22. Triad group 13, includes gas regenerator 23, and air regenerators 24, 25. And similarly for the other regenerator groups. Each gas regenerator is supplied with weak gas thru its conduit 140, 170, 230, etc., extending to the oven faces, and lying beneath and parallel to the regenerator and communicating therewith by means of ports 140a. The air regenerators are similarly supplied with air thru their conduits 150, 160, etc. and ports 150a.

The gas generator 14, is directly connected by means of two passageways 26, 27, with the flues of two neighboring heating walls. In the form illustrated in Figs. 1-8, passage-

way 26 connects gas regenerator 14, to the branches 5, 5a, 5b, of the twin flues of one heating wall and passageway 27 connects the gas regenerator 14, to branches 6, 6a, 6b, of the neighboring heating wall. A series of 70 such passageways 26, 27, directly connects regenerator 14, with a series of twin flues in each heating wall (see Figure 3).

Air regenerator 15, is directly connected by passageway 28, with a twin flue 5, of one heating wall, and air regenerator 16, is directly connected by passageway 29, to a twin flue 6, of the neighboring heating wall. In a similar way, air regenerator 15, is directly connected by passageways 28 to the twin flues of 80 the one heating wall, and air regenerator 16, is directly connected by passageways 29 to the twin flues of the neighboring wall. By these means the resistance of the passage of the gases thru the flues is kept low and the 85 height of the oven is reduced.

The regenerators 17, 18, 19 of group 12, and the regenerators 20, 21, 22 of group 10, are similarly connected to twin flues, group 10 and group 12, being the groups on opposite 90 sides of and adjacent to the feeding in group 11. Consequently, preheated gas and air is supplied by the feeding in group, burnt in neighboring flues and discharged into two groups of regenerators adjacent to and on 95 opposite sides of the feeding in group.

The roof 200 of the regenerators lying between the bottoms of the heating flues and the tops of the regenerators are thus provided with transverse passageways passing transversely through the roof directly connecting the regenerators with the associated twin flues. This insures a short passage for the travel of the gas and air and of the burning gases in the flues, thus reducing the pressure 100 required to feed the flues and with a consequent reduction in leakage between the flue chamber and the oven chamber.

On reversal of the oven, the feeding in groups become the discharge groups for the 110 products of combustion and the adjacent groups become feeding in groups for their respective flue systems.

When it is desired to operate the oven by means of a strong gas, horizontal gas supply 115 pipes 30, 31, are provided which extend in the vaulted passageways underneath the oven, the pipes lying beneath the heating walls. The pipes are arranged in pairs and vertical gas pipes 32, 33, are connected in two sets to the respective horizontal pipes 30, 31. These vertical gas pipes pass upwardly thru the partition walls 34 between the regenerators such as the oven supporting walls, 120 which protects the gas within the pipes from excessive heat which would otherwise lead to decomposition of the gases. One set of vertical gas pipes enters one branch of the twin flues and another set of pipes enters the other 125 130

branch, thus supplying strong gas for both direct and reverse operations of the oven.

In the form of oven above described, the burning gases discharge downwardly into the 5 descending branch of one twin flue and flow upwardly thru the adjacent ascending branch of the neighboring twin flue.

In accordance with another form of the invention as illustrated in Figure 11, the 10 generators and conduits are so constructed that the burning gases flow upwardly and in the same direction in adjacent branches of adjacent twin flues and flow downwardly and in the same direction in adjacent branches of 15 adjacent flues. In other words, the upwardly burning flue branches are adjacent and the downwardly discharging flue branches are likewise adjacent.

I also arrange the air flues which supplies 20 pre-heated air to one branch of the twin flue, back of and below the gas flue, which supplies preheated gas to the same branch of the twin flue. In this way a greater longitudinal separation is provided between the gas flue and 25 the waste-heat flue, thus reducing the danger of leakage between the gas flue and the waste-heat flue.

Referring now to Figure 11, it will be observed that the regenerator system is divided 20 into groups of three regenerators as before, one for gas which lies between two air regenerators. The gas regenerators 39, 40, 41, 42, have arranged adjacent to them on each side thereof, air regenerators 43, 44, 45, 46, 47, 35 etc. The adjacent branches 48, 49, of adjacent twin flues 47a, 48, 49, 50, etc. are supplied with gas from the same gas regenerator 39, thru conduits 51, 52. Air for combustion is supplied to the same flues thru air regenerator 43, thru conduits 54, 55. The air conduits are under the gas conduits as shown in Figure 12. The burning gases thus ascend in adjacent branches of neighboring flues and descend in the remote branches of these flues.

45 The descending burning gases also run in the same direction in adjacent branches of adjacent twin flues. In Figure 11, the descending burning gases pass into air regenerator 44 and gas regenerator 40, thru conduits 56, 57, from one flue and the descending gases in the adjacent branch of the neighboring twin flue pass in the same direction, into the same air regenerator 44, and gas regenerator 40, thru conduits 58, 59. The arrows 50 at the top of the figure show the direction of travel of the burning gases during the oven operation.

55 At each front face of the oven more air and gas is supplied than thru the interior flues in order to supply more heat to the front sections which are subjected to the cooling influence of radiation toward the outside of the oven. An additional air flue 60 and gas flue 61, is supplied for the outside branch of the 60 twin flue, as well as for the inside branch (see

flues 62, 63)—the former operate to supply gas and air during one operation of the oven and the latter supply gas and air during the oven reversal.

The regenerators of the coke oven are divided in the middle by a division wall 300 70 each longitudinal half of the oven thus operating independently of the other half.

In Figures 9 and 10, I have shown my improved form of brick regulator for controlling the flue opening and to regulate the flow of burning gas thru the flue. A brick 65 is placed in a socket in the top of the flue separation wall and extends to the top of the oven. An opening 67, is provided in the roof of the oven, thru which the brick may be introduced. Filling bricks 68, are placed in the opening on top of the valve brick 65. The brick as shown in Figure 10, is narrower than the flue passageway and thus leaves 80 openings 69, 70, at each side thru which the flame passes. The brick may also be perforated. By introducing bricks of various sizes, the flow may be controlled.

Having thus described the invention and 90 its operation, it will be understood that changes may be made in carrying the invention into effect, without departing from the principle thereof.

What I claim is:

A coke oven provided with a roof, a series 95 of alternate coking chambers and heating walls therefor, said walls being each provided with vertical combustion flues, communicably connected at their tops, separating walls between two adjacent combustion flues, a removable brick mounted on the top of each separating wall and extending substantially to the roof of the oven, said brick being adapted to permit the passage of gas at least 100 on one side thereof and being adapted to regulate the rate of passage of burning gas from one flue to the adjacent flue.

In witness whereof I have signed my name to this specification.

CARL OTTO.
